CLAMPING DEVICE

Harvey Jellies, Clarendon Hills, Ill., assignor to
Western Electric Company, Incorporated, New
York, N. Y., a corporation of New York

Application September 12, 1940, Serial No. 356,563

11 Claims.

(Cl. 24—17)

This invention relates to clamping devices and more particularly to devices for clamping strands or cables on their supporting framework.

It is an object of the present invention to provide a simple and relatively inexpensive means for clamping cable or strands in place on their supporting framework.

In accordance with one embodiment of the invention, upright members having integrally formed clamps on the lower end thereof are provided which are substantially channel-shaped in cross section, the flanges of the channels being serrated to receive cross members or horizontal members which are slotted to engage in the serrations on the flanges of the vertically disposed members. The vertically disposed members are provided with suitable slots adapted to receive tongues formed on similarly shaped extensions if it is desired to pile cable or strands on a supporting framework in groups which are higher than the length of the vertical channel members.

A better understanding of the invention will be had from the following detailed description when considered in conjunction with the accompanying drawings, wherein

Fig. 1 is a side elevational view of a section of the cable run showing a portion of the cable supporting framework with clamps made in accordance with the present invention fixed thereto and supporting and clamping the cable on the cable supports;

Fig. 2 is a sectional view taken on the line 2—2 of Fig. 1 in the direction of the arrows showing the end elevation of the upright portion of the clamping devices in some detail;

Fig. 3 is a perspective view of one of the horizontal details utilized in connection with the vertically disposed members to clamp the cable in position;

Fig. 4 is an enlarged fragmentary sectional view through a cable run showing on an enlarged scale, the manner in which the horizontally and vertically disposed members were interconnected;

Fig. 5 is an end view looking toward the right end of the structure shown in Fig. 4;

Fig. 6 is a view in plan on an enlarged scale of the juncture of the horizontally and vertically disposed clamping details;

Fig. 7 is a fragmentary side elevational view of the vertical detail having one of the vertical extensions fixed thereto; and

Fig. 8 is a sectional view taken on the line 8—8 of Fig. 7 in the direction of the arrows.

Referring to the drawings, wherein like refer-

ence characters designate the same parts throughout the several views, the clamping devices which embody the features of the present invention are shown clamping telephone cables on their supporting racks to which the particular clamping devices shown herein are particularly adaptable. As shown in Figs. 1 and 2, the clamps are used to secure cables 10, of varying sizes, to cross members 11 and 12 of a cable rack. Cable racks of this type may consist of a plurality of channel members positioned at spaced intervals and supported in any suitable manner in a telephone exchange.

In the preferred form, the clamping device 15 comprises a plurality of horizontal members, designated generally by the numeral 14, and a plurality of vertically disposed members, designated generally by the numeral 15. If it is desirable to lay more cable on a rack, including the channel members 12, than may be positioned within the length of the vertically extending members 15, an extension member, designated generally by the numeral 16, may be utilized.

The vertically disposed members 15 are formed of sheet metal to substantially channel shape and, as most clearly shown in Figs. 4, 5 and 6, the members 15 have a web 17 and two flanges 18 and 19. The flanges 18 and 19 are serrated and the rounded serrations are disposed in staggered relation, as most clearly shown in Fig. 5, the apex of the serration on the flange 19 being directly opposite the valley or low portion of the corresponding serration on the flange 18. The bottom of each of the members 15 has formed integrally with it a bent-over portion 22, which is disposed at right angles to the web 17 of the member 15 and the portion 22 has extending outwardly from it (to the right and left, Fig. 5) clamping portions 23 and 24 which may be bent to the configuration as shown in Fig. 5 where the portion 23 is rounded, as shown at 26, to engage the right hand flange channel member 12 and the portion 24 is bent to form a spring clip whereby when the rounded portion 26 of the portion 23 is hooked under one flange of the channel member 12, the member 15 may be rocked to the position shown and will be locked in place by a portion 24.

Adjacent its upper end, each of the members 15 is provided with a pair of slots 30 and 31 and a portion 32 of the web 17 thereof is formed out of its normal plane between the slots 30 and 31 to receive a tongue 33 formed by an extending portion of a flange 34 of the extension member 16, which is locked in place by portion 47 there-

of. The portion 47 of the flange 34 is formed out of the normal plane of the flange adjacent the lower end of the portion 32. The extension member 16 is otherwise of the same shape as the vertically disposed clamping member 15.

The horizontal clamping members 14 are all of exactly the same construction, made in varying lengths, as most clearly shown in Fig. 3, and comprise a web 40 and offset edge portions 41 and 42, which serve to strengthen the member 14 and provide a small space between the various layers of cable clamped in place by the vertical members 15 and horizontal members 14. Adjacent their ends, each of the members 14 has an irregularly shaped slot formed in it, as indicated generally at 43. These slots are cut into the member 14 from opposite sides and taper to a point as shown at 44 so that when the members 14 are placed in position, as most clearly shown in Fig. 6, the tapered portion 44 will engage the side of the flange 19 or the flange 18, if the horizontal member is slipped into place from the opposite side. In order that the members 14 may be readily slipped in place on the members 15, the slot 43 extends from a point in one of the offset edge portions toward the other offset edge portion and slightly toward the adjacent end of the member 14. The lip 45, formed as a consequence of the formation of the slot 43, has a notch 46 formed in it which is adapted to engage in the valley between serrations on the flange 18 or 19, as shown in Fig. 6.

Since the serrations formed in the flanges 18 and 19 are staggered with respect one to another, the portion 44 will, when the members 14 are assembled with the members 15, engage the low point of the serrations on the flange 18 or 19, as shown in Fig. 5, and the notch 46 may be engaged with the serrations midway between the crest and valley of the serrations when the member 14 has been locked in place on the member 15. In moving the lip 45 into this position, it will be necessary, of course, to bend the lip downwardly (Fig. 5) until the notch 46 passes the edge of the serraion, whereupon the lip may be released through its resiliency and tightly clamp the member 14 on the member 15. When it is desired to remove any of the members 14 from the vertical members 15, it is simply necessary to bend the lip 45 downwardly and slip the member 14 off of the member 15 since, when the lip 45 is midway downwardly, the notch 46 therein will be out of the path of the higher portions of the serrations in the member 18 or 19.

Although a specific embodiment of the invention has been described hereinbefore, it will be understood that modifications and adaptations thereof may be made without departing from the invention, which is to be limited only by the appended claims.

What is claimed is:

1. A clamping device comprising upright members having bent-over portions with serrated edges, and cross members having slots adjacent their ends in registration with the serrated edges on the bent-over portions of the upright members.

2. A clamping device comprising upright members of substantially channel-shaped cross section and having the flange portions thereof serrated, and cross members having slots adjacent their ends gripingly engaging the serrated edges formed on the flanges of the upright members.

3. A clamping device comprising upright members having bent-over portions with staggered

serrations on the edges of said bent-over portions, and cross members having slots adjacent their ends in engagement with the serrated edges on the upright members.

5. A clamping device comprising upright members having bent-over portions with staggered serrations on the edges of said bent-over portions, and cross members having slots adjacent their ends in engagement with the serrated edges 10 on the upright members, said slots in the cross members being less in width than the distance from the base of the web to the tips of the serrations on the upright members to provide surfaces to grip the serrated part of the upright members.

5. A clamping device for holding strands or cables on frames comprising upright members having integrally formed clamps thereon gripingly engaging the frame, said upright members comprising a web portion and angularly disposed flange portions having serrations thereon, a series of toothlike projections on said flange portions, the projections being arranged to project at alternate levels on the flanges, and cross members slotted to engage said upright members.

6. A clamping device comprising upright members having bent-over portions with serrated edges, the serrations on said serrated edges 30 extending at alternate levels on opposite bent-over portions, and cross members having slots adjacent their ends in registration with the serrated edges on the bent-over portions of the upright members.

7. A clamping device comprising upright members having bent-over portions with serrated edges, the serrations on said serrated edges extending at alternate levels on opposite bent-over portions, cross members having slots adjacent their ends in registration with the serrated edges on the bent-over portions of the upright members, and a notch cut in said slot to provide locking surfaces engageable in the valleys between the serrations.

8. A clamping device comprising upright members having bent-over portions with serrated edges, the serrations on said serrated edges extending at alternate levels on opposite bent-over portions, cross members having slots adjacent their ends in registration with the serrated edges on the bent-over portions of the upright members, and a notch formed in the side of each of said slots on the side thereof closest to the end of the cross member to provide a locking surface for engagement with the sloping side of one of the serrations.

9. A clamping device for clamping cable on frames comprising upright members having a web portion and oppositely disposed and angularly projecting flange portions, said flange portions having their edges serrated, and cross members in attachment to said upright members, said cross members comprising a main body portion and end portions integrally connected to the main body portions by a connecting portion whereby the upright and cross members may be locked together by bending the end portions out of their normal plane and forcing the cross member in opposite directions onto opposite upright members.

10. A clamping device for holding strands or cables on a frame including spaced channel-shaped members supported by and extending at an angle to said frame, said channel-shaped

member having its flanges oppositely directed and formed to have a series of similarly spaced notches in their edges, the notches in the edges of the two flanges on each member being offset relative to each other, and an element cooperating with and extending across a frame in engagement with channel-shaped members on said frame to hold cables on the frame.

11. A clamping device for holding strands or cables on a frame including spaced channel-shaped members supported by and extending at

an angle to said frame, said channel-shaped member having its flanges oppositely directed and formed to have a series of similarly spaced notches in their edges, the notches in the edges of the two flanges on each member being offset relative to each other, and an element having slots adjacent its ends and extending from opposite sides at opposite ends in locking engagement in the notches in the edges of the flanges of the channel-shaped member.

10 HARVEY JELLIES.
